US00D849925S

(12) **United States Design Patent** (10) Patent No.: **US D849,925 S**
(45) Date of Patent: **** May 28, 2019**

(54) **FAN**

(71) Applicant: **DELTA T CORPORATION**,
Lexington, KY (US)

(72) Inventors: **Ernest John Noble**, Selangor (MY);
Ken Siong Tan, Selangor (MY); **Jon**
Jet Ling, Selangor (MY); **Seng Rui**
Chan, Selangor (MY)

(73) Assignee: **DELTA T, LLC**, Lexington, KY (US)

(**) Term: **15 Years**

(21) Appl. No.: **29/633,558**

(22) Filed: **Jan. 15, 2018**

Related U.S. Application Data

(63) Continuation of application No. 29/562,520, filed on
Apr. 26, 2016, now Pat. No. Des. 808,004, which is
a continuation of application No. 29/531,907, filed on
Jun. 30, 2015, now Pat. No. Des. 770,027.

(57) **CLAIM**

The ornamental design for a fan, as shown and described.

DESCRIPTION

FIG. 1 is a bottom perspective view of the fan;

FIG. 2 is a top perspective view of the fan;

FIG. 3 is a front view of the fan;

FIG. 4 is a right side view of the fan;

FIG. 5 is a rear view of the fan;

FIG. 6 is a left side view of the fan; and,

FIG. 7 is a top view of the fan.

The broken lines shown in the drawings illustrate the fan that
form no part of the claimed design.
